UNITED STATES PATENT OFFICE.

CHARLES A. COMP, OF DETROIT, MICHIGAN, ASSIGNOR TO BUHL STAMPING COMPANY, OF DETROIT, MICHIGAN, A CORPORATION OF MICHIGAN.

MILK-CAN COVER AND METHOD OF FORMING THE SAME.

Application filed September 21, 1925. Serial No. 57,772.

The invention relates to can covers more particularly designed for closures of milk cans and the invention consists in the construction and method of forming the same as hereinafter set forth.

In the drawings;

Figure 1 is a central longitudinal section through the cover.

Figures 2-5 are diagrammatic views showing successive steps in the method of forming the cover.

In the manufacture of closures for milk cans it is very essential to avoid the formation of any crevice in which dirt might lodge to render the device insanitary. It is also usual to form such covers with a portion for fitting within the neck or mouth of the can and a bell shaped flange overhanging and protecting the mouth of the can.

My improved construction is designed to avoid the formation of crevices and at the same time to secure a strong attachment between the cover proper and the bell shaped flange. It is also an object to obtain a construction which may be easily manufactured.

In detail A is the cover proper which is preferably drawn from a sheet metal blank to form the integral end A' and annular flange A² with a rounded fillet B connecting the same. C is the bell shaped flange which is first formed as shown in Figure 2 from an imperforate sheet metal blank fashioned with a recess D therein corresponding in diameter to the external diameter of the flange A². The web E of the recess portion is then cut away as shown in Figure 4 leaving an annular flange F adapted to closely fit the flange A² of the member A. The members A and C may then be united by suitable means such as spot welding or riveting after which the whole structure is tinned. The outer edge of the bell shaped flange C is provided with the usual bead G.

With the construction as just described the only part of the structure which is exposed to the milk is the inner surface of the member A including the flange A² thereof. This inner surface is free from any crevice and the rounded fillet B will not permit the retention of dirt therein. On the outside of the cover a crevice may be formed between the members A and C but as this is never exposed to contact with the milk it is not ob-

jectionable. Mechanically the structure is exceptionally strong due to the integral construction of the head A and flange A² together with the wide bearing of the flange D thereon.

What I claim as my invention is:

1. A closure comprising a pressed sheet metal blank having an integral head portion, annular cylindrical flange portion and rounded fillet therebetween and a bell flange member having an inturned portion externally connected to said first mentioned member and forming a reinforcement adjacent said rounded fillet.

2. A closure comprising a pressed sheet metal member having an integral head portion, an annular cylindrical flange portion with a rounded fillet therebetween and a bell flange member provided with an inturned cylindrical flange externally fitting and secured to said first mentioned member adjacent said fillet.

3. A closure comprising a pressed sheet metal flange having an integral end portion, annular cylindrical flange portion and a rounded fillet therebetween, and a bell flange member having a beaded outer edge and a reversely bent cylindrical flange at its inner edge fitting and externally secured to the cylindrical flange of said first mentioned member adjacent the said fillet, forming a double ply structure adjacent said fillet and providing a guard extending laterally in the horizontal plane of said fillet.

4. The method of forming closures comprising the pressing of a sheet metal blank to form a cylindrical flange and integral head, pressing a second blank to form a cylindrical recess with an integral web and a surrounding bell shaped flange, removing the web portion telescopically engaging the remaining cylindrical flange with the cylindrical flange of the first member and securing the same together.

5. The method of forming closures comprising the pressing of a sheet metal blank to form a cylindrical flange and integral head, pressing a second member to form a cylindrical recess corresponding to the external diameter of the cylindrical flange of said first member, and with an integral web or bottom through said recess, forming an annular bell flange on said second member,

- removing the web or bottom of the recess portion and engaging and securing the cylindrical flange upon the cylindrical flange of the first mentioned member.
- 5 6. The method of forming closures comprising the pressing of a sheet metal blank to form a cylindrical flange with an integral head, pressing a second member to form a cylindrical recess to fit the external diameter of said first mentioned member and having an integral central web or bottom, said member being also formed with a surrounding bell flange having a beaded lower edge, removing the web or bottom of said recess and engaging the cylindrical flange of
- 10 the second member with the cylindrical flange of the first member and securing these parts to each other.
- 15 7. A closure comprising a cup-shaped member having integral side and bottom walls, and a flange member having annular walls acutely arranged with respect to each other, one wall of the said flange member being bell-shaped and the other wall being straight and being adapted to be secured to the outer periphery of the side wall of the cup-shaped member.
